UNITED STATES PATENT OFFICE.

ELI BEAUDIN, OF LAONA, WISCONSIN.

RAILROAD RAIL.

Application filed November 30, 1923. Serial No. 677,742.

To all whom it may concern:

Be it known that I, ELI BEAUDIN, a citizen of the United States, residing at Laona, in the county of Forest and State of Wisconsin, have invented a new and useful Railroad Rail, of which the following is a specification.

This invention aims to provide a simple means whereby the ends of a pair of railroad rails may be connected without resorting to bolts.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that, within the scope of what is claimed, changes in the precise embodiment of the invention shown, can be made, without departing from the spirit of the invention.

In the accompanying drawings:—

Figure 1 shows in top plan, a device constructed in accordance with the invention, parts being broken away so that the view, in part, is a horizontal section; Figure 2 is a transverse section; Figure 3 is a perspective view showing one of the connecting plates; Figure 4 is a transverse section showing a modification; Figure 5 is a perspective view disclosing the connecting plate used in Figure 4.

Referring to Figures 1, 2 and 3, there is shown a combined chair and clamp 1 comprising a base 2 provided with an overhanging bracket 3 and equipped with an upstanding lug 4; the lug 4 carrying a tightening device 5, such as a screw. Openings 6 are formed in the base 2 of the chair and clamp 1 and are located between the bracket 3 and the lug 4. Seats or notches 7 are fashioned in the ends of the base 2.

Connecting plates, in the form of angle bars 8 and 9 are provided. The angle bar 8 has a lateral flange 10 and an upstanding flange 11. The angle bar 9 has a lateral flange 12 and an upstanding flange 14. Recesses 15 are fashioned in the lower surfaces of the flanges 10 and 12 of the angle bars.

The flanges 11 and 14 of the angle bars have upwardly inclined projections 16. Notches

17, or seats, are formed in the outer edges of the flanges 10 and 12 of the angle bars. The flanges 10 and 12 of the angle bars have openings 18 adapted to be aligned with the openings 6 in the base 2 of the chair and clamp 1. The lateral flange 12 of the angle bar 9 has an upstanding rib or abutment 20.

The base flanges of a pair of rails 21 rest on the base 2 of the chair 1. The outer edges of the flanges 12 and 10 of the angle bars 9 and 8 rest on the base 2 of the chair and clamp 1, the edges of the base flange of each rail 21 being received in one of the recesses 15 which are formed in the flanges 10 and 12. The outer edge of the flange 10 of the angle bar 8 is engaged beneath the bracket 3 on the base 2 of the chair and clamp 1. The screw 5 overhangs the outer edge of the flange 12 of the angle bar 9 and abuts against the rib 20 on the flange 12. The flange 11 of the angle bar 8 and the flange 14 of the angle bar 9 extend upwardly along the webs of the rails 21 and engage the balls of the rails, as shown in Figure 2, the projections 16 on the flanges 11 and 14 of the angle bars being received in the bolt openings 22 of the rails 21, the projections on the flange 11 alternate with the projections on the flange 14, as clearly indicated in Figure 1.

It will be obvious that when the screw 5 is advanced, the projections 16 will be held engaged with the openings 22 of the rails 21, and a secure joint will be effected. If the member 1 is located on a tie, spikes may be driven through the aligned openings 18 and 6. Spikes also may be driven in the tie, the last specified spikes being engaged in the seats of notches 7 of the member 1. If the member 1 happens to be located otherwise than upon a tie, spikes may be driven into the tie, the spikes being mounted in the seats or notches 17.

In the form shown in Figures 4 and 5, parts hereinbefore described have been designated by numerals previously used, with the suffix "a". Connecting plates 24 and 23 are provided and have recesses 25, corresponding to the recesses 15. Notches 26 correspond to notches 17, the openings 27 corresponding to the openings 19, and the openings 28 correspond to the openings 18. The plates 23 and 24 have upwardly inclined projections, adapted to be mounted in the bolt openings 22a of the rails 21a, the projections 29 having upstanding vertical fingers 30

adapted to engage opposite sides of the web of the rail 21^a, the plate 24 being provided with a rib 31 adapted to cooperate with the screw 5^a. The operation of the device shown in Figures 4 and 5 will be understood readily from what has been stated hereinbefore in connection with that form of the invention which appears in Figures 1, 2 and 3. The form shown in Figure 4 may be used when a temporary track is laid, or under any other conditions which do not call for the extreme security afforded by that form of the invention which is delineated in Figures 1, 2 and 3.

15 The clamp and chair 1 may be disposed adjacent to either end of the plates 8 and 9, and then the openings 19 and 6 of Figures 1 and 2, or the openings 27 of Figure 5 and the corresponding openings in the member 20 1^a, are alined for the reception of spikes.

Having thus described the invention, what I claim is:

1. In a device of the class described, connecting plates having oppositely extended 25 lateral projections for engagement with the

bolt holes of rails, and a base supporting the plates, the base and the plates having alined openings for the reception of spikes.

2. In a device of the class described, connecting plates having oppositely extended 30 lateral projections for engagement with the bolt holes on rails, the projections being provided with integral fingers disposed at an angle to the projections and adapted to engage the opposite sides of the webs of rails, 35 a base supporting the plates, the base being provided with a fixed projection engaging one plate, and being provided with a second fixed projection, and a screw threaded into the second projection and engaging the other 40 plate.

In testimony that I claim the foregoing as my own, I have hereto affixed my signature in the presence of two witnesses.

ELI ^{bis} X BEAUDIN.
